UNITED STATES PATENT OFFICE.

JOHN MANU, OF DETROIT, MICHIGAN.

DESIGN FOR A FORGED-STEEL VEHICLE-WHEEL.

57,246.

Specification for Design.

Patented Mar. 8, 1921.

Application filed June 16, 1920. Serial No. 389,495. Term of patent 7 years.

To all whom it may concern:

Be it known that I, JOHN MANU, a citizen of the United States, residing at Detroit, county of Wayne, and State of Michigan, have invented a new, original, and ornamental Design for Forged-Steel Vehicle-Wheels, of which the following is a specification, reference being had to the accompanying drawing.

Figure 1 is an elevation of the obverse side of a forged steel vehicle wheel showing my new design.

Fig. 2 is a perspective view thereof showing particularly the reverse side.

I claim:

The ornamental design for a forged steel vehicle wheel, as shown.

JOHN MANU.
